UNITED STATES PATENT OFFICE.

WILLIAM H. PEPPER AND ALBERT T. L. DAVIS, OF LACONIA, NEW HAMPSHIRE.

DESIGN FOR A PATTERN FOR KNIT FABRIC.

SPECIFICATION forming part of Design No. 25,493, dated May 12, 1896.

Application filed March 6, 1896. Serial No. 582,144. Term of patent 7 years.

To all whom it may concern:

Be it known that we, WILLIAM H. PEPPER and ALBERT T. L. DAVIS, of Laconia, in the county of Belknap and State of New Hampshire, have invented and produced a new and original Design for a Pattern for Knit Fabrics, of which the following is a specification.

Our new and original design for a pattern for knit fabrics is illustrated in the accompanying drawing, which shows a plan view of a knit fabric with the designed pattern applied thereto.

As shown in the drawing, the pattern is composed of diamond-shaped blocks A B, arranged alternately along diagonal lines; or, in other words, the blocks A are arranged in longitudinal rows, and the blocks B are likewise arranged in longitudinal rows, but staggered with reference to the blocks A. Each diamond-shaped block A is composed of parallel wales *a b* of contrasting shades or colors, the wales *a* being the predominating and characteristic ones. The central wale *a* of the several blocks A B in one longitudinal row is continuous throughout all the blocks in the row. Each block B has a central space *c* and a border *d*. The central space *c* is, like the blocks A, composed of parallel wales *a b* of contrasting shades or colors, the wales *a* being the predominating and characteristic

ones. The border *d* surrounds the four sides of the central space *c* and is composed of attenuating stripes *e f* of contrasting colors or shades. Said stripes *e f* are perpendicular to the wales *a b*. The stripes *e* are of the same shade or color as the wales *a*, and the stripes *f* are of the same shade or color as the wales *b*.

The essential feature of the pattern consists of the diagonally-alternating diamond-shaped blocks, one half being composed of parallel wales of contrasting colors or shades, while each of the alternating diamond-shaped blocks of the other half is composed of a central portion or space composed of parallel wales of contrasting shades or colors, surrounded on all four sides by a border composed of parallel stripes of contrasting shades or colors perpendicular to the said wales.

We claim as our invention—

The design for a pattern for knit fabrics, as shown and described.

In witness whereof we have hereunto signed our names in the presence of two subscribing witnesses.

WILLIAM H. PEPPER.
ALBERT T. L. DAVIS.
